UNITED STATES PATENT OFFICE.

MARMONT B. EDSON, OF BROOKLYN, NEW YORK.

SPEED RECORDER AND INDICATOR.

SPECIFICATION forming part of Letters Patent No. 240,109, dated April 12, 1881.

Application filed September 10, 1880. (No model.)

To all whom it may concern:

Be it known that I, MARMONT B. EDSON, of Brooklyn, in the county of Kings and State of New York, have invented a new and useful Improvement in Speed Indicators and Recorders, of which the following is a specification.

The object of my invention is to obtain a constant indication and permanent record of the speed of machinery. For this purpose I combine with indicating and recording mechanism of usual character devices fitted for rotary motion by connections to the machinery, and provided with weights fitted for centrifugal motion, that are in connection with the actuating-rod of the indicating mechanism, whereby the indicating-hand and recording-pencil are moved in unison with the centrifugal motion of the weights.

My invention consists in the combination of the devices named, the construction and operation of which are set forth in detail hereinafter, with reference to the accompanying drawings, forming part of this specification.

In the drawings, Figure 1 is a front elevation of the machine, and Fig. 2 is a side elevation, partially in section.

Similar letters of reference indicate corresponding parts.

The indicating and recording mechanism is substantially similar to that shown in Letters Patent heretofore granted to me, and in common use for recording steam-pressure. Being well known, I will describe such mechanism only in a general way; and it is to be understood that the indicating-hand may be dispensed with, and the recording-pencil used alone, if desired.

A is the stand, on which are fitted the drums *a a* that carry a belt, *b*, of paper, moved by clock-work contained in case B, and connected with one of the drums *a*.

c is a rock-shaft actuating the hand *d* by a cogged segment, *e*, and carrying an arm, *f*, that gives movement to the pencil-arm *g*.

C is alarm mechanism provided with stop-lever *h*, that is moved by contact of arm *i* from shaft *c*. The shaft *c* is fitted with an arm from which a rod, *k*, depends, which rod is in connection with the operating devices next described.

To the under side of stand A is fixed a tubular post, *l*, carrying at its upper end a loose pulley, *m*, sustained by a collar, *n*, and at its lower end a flanged sleeve, *o*, which is loose upon the post, and is sustained by two spring-arms, *p*, that are connected with pulley *m* and sleeve *o*. The sleeve *o* extends below the end of post *l*, and its central aperture is formed with a ring-flange, *o'*, forming a guide for the rod *k*, which extends through post *l* and sleeve *o*. The end of rod *k* is fitted with a circular disk, *k'*, or ring, that is clamped between the lower end of sleeve *o* and a screw-cap, *q*, on the sleeve, so that the sleeve and rod shall rise and fall together. The spring-arms *p* are provided with balls *r* at their mid-length. Upon post *l* is a fixed collar, *s*, that limits upward movement of sleeve *o* on the post. 55 60 65

The pulley *m* is to be connected by a belt or gearing with the engine or machine, and thereby rotation given to the pulley, sleeve *o*, and arms *p*. The balls *r* will, in operation, be thrown out more or less by centrifugal action, the sleeve *o* and rod *k* correspondingly moved, and the indicating and recording devices thus 70 75 operated.

I do not not limit myself to the mechanism and connections exactly as described, as they may be varied within the scope of my invention. The devices for obtaining centrifugal action may be of different construction, and the rod *k* may be connected directly to the pencil-arm, and the indicating-hand dispensed with.

This speed-indicator can be combined with pressure indicating and recording instruments by placing the post *l* at one side of the center of the base and extending rod *k* through the base to a pencil-arm fitted for marking the speed upon the paper or chart on which the pressure is recorded by a separate pencil, in the ordinary manner. By this combination an instrument is obtained which furnishes separate records of pressure and of speed upon a chart graduated to indicate the time. 85 90 95

Having thus fully described my invention, I claim as new and desire to secure by Letters Patent—

1. The combination, with indicating and recording mechanism, substantially as described, 100

of the rod *k*, having disk *k'*, the post *l*, the loose pulley *m*, the collars *s n*, the loose flanged sleeve *o*, having screw-cap *q*, the spring-arms *p*, having balls *r*, and the ring-flange *o'*, as and 5 for the purpose specified.

2. In speed indicators and recorders, the post *l*, loose pulley *m*, loose sleeve *o*, and weighted

spring-arms *p*, substantially as described, combined together and with the actuating-rod *k* of the indicator for operation, as specified.

MARMONT B. EDSON.
